(57) **CLAIM**

The ornamental design for a watch dial, as shown and described.

DESCRIPTION

FIG. 1 is a right-top perspective view of the watch dial;

FIG. 2 is a top view of the watch dial;

FIG. 3 is a left side view of the watch dial;

FIG. 4 is a right side view of the watch dial;

FIG. 5 is a front view of the watch dial; and,

FIG. 6 is a rear view of the watch dial.

The broken lines in FIGS. 3, 4, 5, and 6 are used to show portions of the watch dial that do not form part of the claimed design.

1 Claim, 4 Drawing Sheets

FIG. 1

FIG. 2

FIG. 3

FIG. 4

FIG. 5

FIG. 6
